UNITED STATES PATENT OFFICE

MILTON C. BALDER, OF YONKERS, NEW YORK

ELECTRIC SIGN

Application filed May 16, 1930. Serial No. 452,845.

This invention relates to improvements in electric signs, the principal object of the invention being to provide a sign of this character which is comparatively simple in construction, inexpensive to manufacture and possessed of maximum visibility.

A further object of the invention is to provide an electric sign in which the angle of the sign-bearing member proper can readily be varied to correspond with the position of the observer and without changing its position relative to the lighting means.

Other means and advantages of the invention will appear as the description proceeds.

15 In the drawings accompanying this specification,

Fig. 1 is a partly broken away perspective view of a sign embodying the features of the present invention;

20 Fig. 2 is a transverse sectional view illustrating the sign bearing panel swung outward on its hinges to afford access to the lamp bulbs;

Fig. 3 is a broken away transverse sectional view of the panel on a larger scale; and

Fig. 4 is a front view of one section of a modified form of panel and illustrating also a modified type of letter.

30 Referring to the drawings, 1 designates an elongated housing, which may be of any desired material and size. One side of the housing is entirely open, and hinged, preferably to the bottom of the housing, is a

35 frame 2 adapted to be swung into said open side. Secured to the top and bottom bars of the frame so as to be movable therewith is a semi-tubular member 3 of sheet metal and preferably having a reflecting surface.

40 By this construction the frame may be moved so as to carry the member 3 from the position indicated in broken lines in Fig. 2 to the position shown in full lines, or even further. Supported in the semi-tubular

45 member 3 are a plurality of reflectors 4 at the center of each of which is supported an electric light bulb 5, the reflectors being of such form as to spread or diffuse the light evenly through the open side of the housing.

50 1. The top of the housing is provided with

an overhanging portion or hood 6 having a curvature coincident with that of the member 3, whereby said member will maintain contact with the hood when in its outermost position. Current is supplied to the lamps 5 by wires 7 which pass through openings in the rear wall of the housing 1.

Hinged within the frame 2 and preferably to the top bar thereof is a second frame

8 the members of which are of channel formation whereby the frame is adapted to retain a pair of panels 9 and 10 which carry the sign to be exhibited. After numerous experiments I have found that the results obtainable are influenced materially not only by employing two translucent panels of different types arranged in juxtaposition, but also by the disposition of the sign-bearing panel proper relatively to the light and to its companion panel. In the present instance the panel 9 is a colored translucent panel having a roughened surface on one side, similar to the glass commonly known as cathedral glass, while the panel 10 is the sign-carrying panel proper and is preferably composed of a piece of ground glass.

A black or dark colored background is preferably painted on the panel 10, and the matter to be displayed is blocked out in perspective, as shown in Fig. 1. The face of each letter is divided into three areas, namely a central area of a contrasting color such as yellow, green or any other desired color, said area being enclosed within a border, preferably of a darker color and which

85 border is separated from the surrounding field or background by an unpainted area. This type of lettering imparts to the sign a visibility which renders it readable at a very much greater distance than would be possible with any of the styles of lettering ordinarily used for this purpose. I have found that the sharpness of the letters is considerably emphasized if the cathedral glass panel is placed nearest the light with its roughened side outermost and the ground glass panel inserted with its painted side next to the cathedral glass.

The semi-tubular member 3 is provided with end walls 11 attached to the vertical

members of the frame 2 thereby forming a closed lamp chamber between the frame and said member 3 thus excluding rain, dust and other undesirable material from the 5 lamps and reflectors.

In practice the panel-carrying frame 8 is normally disposed within the frame 2, and the latter is movable on its hinges to different angular positions in the open side of the 10 housing. This adjustability of the frame 2 renders it possible to set the sign panels at the best angle to be viewed in accordance with the height at which the sign may be located above the observer. In Fig. 2 the 15 panel-carrying frame is swung outward on its hinges to permit access to the light chamber for replacing or inspecting the lamps. It will be understood, of course, that the device will be of suitable length to accommodate 20 the matter to be displayed and that the number of lamps and reflectors will vary proportionately to the length of the device. These and other mechanical details of the device may be varied without departing 25 from the spirit and scope of the invention as set forth in the appended claims.

The sign-bearing panel may, if desired, be made up of a plurality of individual sections 12, as shown in Fig. 4, each section 30 carrying a single letter adapted to form part of the sign to be exhibited. In Fig. 4 it will also be noted that the letter is of a different style from those shown in Fig. 1. In other words, the letter presents a full 35 face view comprising a central shaded area enclosed within an unshaded border. I have found this type of letter very effective, since the intermediate shaded portion prevents too great a diffusion of the light, while 40 at certain distances the border on one side of said area appears to merge with that on the other side so completely that the shaded area is entirely invisible.

Having thus described my invention, 45 what I claim is:

1. An electric sign, comprising a housing, a lighting system mounted for angular movement in said housing, a translucent sign-bearing member disposed in fixed relation to said lighting system, and means for varying the angular position of said member and lighting system with relation to the housing.
2. An electric sign, comprising a housing 55 having an open side, a sign-bearing member hingedly mounted for angular movement in the open side of said housing, a lighting system disposed within said housing, and means for maintaining said lighting system in fixed relation to said sign-bearing member.

3. An electric sign, comprising a housing having an open side, a frame hingedly mounted in the open side of said housing 65 and carrying a sign-bearing member, a

member secured to said frame and forming therewith a closed chamber, and a plurality of electric lights supported in said chamber in fixed relation to said sign-bearing member.

4. An electric sign, comprising a housing having an open side, a frame hingedly mounted in the open side of said housing and carrying a sign-bearing member, a semi-tubular member secured at its longitudinal edges to said frame and forming therewith a closed chamber, a plurality of electric lights supported in said chamber in fixed relation to said sign-bearing member, and a reflector for each of said lights adapted to diffuse the light over the surface of said sign-bearing member.

5. An electric sign, comprising a housing having an open side, a frame hingedly mounted in the open side of said housing, a semi-tubular member secured at its longitudinal edges to said frame and forming therewith a closed chamber, a plurality of electric lights supported on said semi-tubular member within said chamber, a translucent panel disposed in said frame and having a sign on that side thereof nearest the lights, and a second translucent panel of a different type disposed in said frame in juxtaposition to the first panel and between it and the lights.

6. An electric sign, comprising a housing having an open side, a frame hingedly mounted in the open side of said housing, a semi-tubular member secured at its longitudinal edges to said frame and forming therewith a closed chamber, a plurality of electric lights supported on said semi-tubular member within said chamber, a second frame hingedly mounted in said first frame and normally lying in the same plane therewith, and a pair of translucent panels disposed in said second frame one having a sign on that side thereof nearest the lights and the other panel disposed in juxtaposition to the sign-bearing side of said first panel and between it and the lights.

7. An electric sign, comprising a housing, a lighting system mounted for angular movement in said housing, a plurality of translucent members each carrying matter to be displayed, said members cooperating to form a complete sign-carrying panel disposed in fixed relation to said lighting system, and means for varying the angular position of said panel and lighting system with relation to the housing.

In testimony whereof I have signed my name to this specification.

MILTON C. BALDER.
